INVENTOR

UNITED STATES PATENT OFFICE.

ALEXANDER FERDINAND VICTOR, OF DAVENPORT, IOWA.

DESIGN FOR A PICTURE-DISPLAY-MACHINE BODY.

42,496.

Specification for Design.

Patented May 7, 1912.

Application filed December 9, 1911. Serial No. 664,880. Term of patent 14 years.

To all whom it may concern:

Be it known that I, ALEXANDER FERDINAND VICTOR, a subject of the King of Sweden, residing at Davenport, in the county of Scott and State of Iowa, have invented a new, original, and ornamental Design for Picture-Display-Machine Bodies, of which the following is a full, clear, and exact description, reference being had to the accompanying drawing, forming a part thereof.

My design relates to a body for inclosing and supporting a picture display mechanism, such as kinematographs, stereopticons, and the like, and has for its object to provide a contrivance of this character that is neat and artistic in appearance, as well as compact and convenient.

In the drawings: Figure 1 is a vertical front elevation of my ornamental design for picture display machine bodies and the like. Fig. 2 is a vertical side elevation thereof. Fig. 3 is a vertical rear elevation of the same.

Referring to the drawings, it will be seen that my design consists of a standard or base of an inverted mushroom shape, the lower spread-out portion forming the base or foundation, and the vertical portion adapted to form a pedestal upon which the box-like casing is mounted. This casing comprises a hollow rectangular-shaped body, the bottom of which is provided

with an embossment that projects downwardly from the central portion thereof, and from which the pedestal depends. Projecting from the rear portion of this embossment is a sickle or substantially L-shaped bracket that extends downwardly and rearwardly and has its outer extremity bifurcated. The vertical front wall of the casing is provided with a centrally located embossment from which the lens of the apparatus protrudes. The rear wall comprises an embossed plate, the central portion of which, in axial alinement with the lens, is provided with a picture opening. The meeting edges and the corners of the walls, except for the embossments mentioned above, are rounded, as shown in the drawings to soften and break the sharp angles and lines of the body and present a more aesthetic appearance thereto. The lower portion or base and pedestal is round in cross-section, substantially as shown.

What I claim is:

The ornamental design for a body for picture display machines, as shown and described.

In witness whereof, I have hereunto set my hand this 15th day of Dec. 1910.

ALEXANDER FERDINAND VICTOR.

Witnesses:

LUCILE PARKER,
S. G. Rose.
